Inventor:

Henry F. Megill

UNITED STATES PATENT OFFICE.

HENRY F. MEGILL, OF BROOKLYN, NEW YORK.

PERCUSSION-STRIP.

SPECIFICATION forming part of Letters Patent No. 227,560, dated May 11, 1880.

Application filed September 12, 1879.

To all whom it may concern:

Be it known that I, HENRY F. MEGILL, of the city of Brooklyn, county of Kings, and State of New York, have invented certain new and useful Improvements in Fulminating or Percussion Strips; and I do hereby declare that the following is a specification thereof, reference being had to the accompanying drawings.

My invention relates to improvements upon the well-known percussion-strips which have pellets of fulminating compound deposited at regular intervals along and throughout their entire length, which are usually made about two feet long and rolled up in a round coil, and in this form applied to use in various kinds of devices for lighting purposes.

Figure 1 is a perspective view of my improved percussion-strip rolled up into a coil with the fastening end projecting therefrom. Fig. 2 represents a side elevation of the machine to which my improvements apply, and which contains my percussion-strip coiled up in the usual way and attached to the winding-wheel according to my improved plan. Figs. 3, 4, and 5 are perspective views of my improved percussion-strips laid flat to show the differential manner of placing the pellets. Fig. 6 is a plan view of the same before they are cut from the sheet.

The object of my invention is to provide percussion-strips with cheap, reliable, and simple means by which they may be securely, but temporarily, attached to a certain recently-patented feeding device in automatic lighters, which is known as the "winding-wheel."

It also has for its object the proper regulation of the pellets within said strips, whereby they may be fed successively to and simultaneously with the falling of the hammer of the machine by said winding-wheel.

My invention therefore consists in providing said percussion-strips with suitable heads or flanges by which they may be fastened between any two of the projections of said winding-wheel, the said projections serving as lugs to take hold of the said heads or flanges and prevent the ends of the strips from drawing through when the strain or draft is applied to them by the turning of said wheel to wind the strips up. These percussion-strips are disposed of, and fresh ones replaced, one after another, and by this means of fastening the

changes are readily and quickly made, which saves considerable trouble to the consumer in using the machine.

Heretofore the percussion-strips were secured to the winding-wheel by looping the blank or loose end around one of the projections on said wheel, which is slow and objectionable, while my invention provides a cheap ready-made attachment.

My invention also consists in placing or depositing the pellets of fulminate within said strips differentially, or at increased distances apart throughout its length.

It is understood that as the strip is wound around said wheel each layer will increase its travel in accordance with the increase of its diameter; and as the hammer does not alter its number of strokes during any of the successive revolutions, the pellets, if placed at regular distances or intervals apart, will eventually arrive at the hammer faster than the hammer will fall, and many will be wasted thereby; but if the strips are made according to my improved plan—say, starting the pellets one-eighth of an inch apart and gradually increasing to three-eighths, or whatever degree is required by the size of the wheel—each pellet will be fed regularly to the hammer and be exploded singly.

In the drawings, A represents my improved percussion-strips. The manner of placing the pellets between two layers of paper, one thick and the other thin, closely pasted together to prevent the explosion of one of the pellets from communicating with the other, is as has been done heretofore, and a represents the thin tissue layer, and b the thicker layer. In accordance with my invention, however, these pellets of fulminate are deposited differentially, beginning at the end to be attached to the wheel, and increasing the space between them toward the other end, as shown in Figs. 3, 4, and 5 by letters c.

B is the loose or projecting end of the percussion-strip A, which is lapped over and around a pad, f, and gummed or pasted singly and firmly together to form a stud or head, C, or the flanges d d, on each side of said strip.

The strips are attached to the winding-wheel, as shown in Fig. 2, by passing the end of the strip edgewise between the projections n, with the stud or head C within the circuit of said

projections, which serve as lugs to take hold of the flanges *d* and draw and wind the said strip upon said wheel.

The pad *f* may be made of any substance or material. I prefer, however, to make said pads of twine or strips of card-board, and while the percussion-strips are in the full sheet draw or lay the said twine or card-board across the ends from one side of the sheet to the other, and fold and secure, as above described, and then cut the percussion-strips from the sheet in the usual manner, as shown by dotted lines in Fig. 6. The said pad may be secured, if desired, within the end of the percussion-strips,

15 by laying and pasting it between the two layers *a* and *b*, and lapping or folding the end of one layer over the other, as shown by Fig. 4.

In Fig. 5 the pad is represented as being made of twine, while in the other figures of

20 card-board.

I do not claim as my invention the percussion-strip in itself, for I know that strips of fulminating or igniting pellets have heretofore existed; but I make certain valuable improvements on said percussion or igniting strips.

25 Neither do I wish my claims to be construed to cover or include strips of any other kind than those which are provided with fulminating or igniting compound which are adapted 30 to automatic lighting devices; nor do I claim the winding-wheel or its projections.

I do not claim the anvil, its bearings, the tension-spring, or any other part of the machine shown in Fig. 2 of the drawings, the said machine being shown simply to illustrate the 35 manner in which my improved percussion-strips are applied.

What I claim is—

1. A percussion or igniting strip provided at the end with a stud, knob, or head by which 40 it may be held by the lugs or projections on the winding-wheel of an automatic lighting device, substantially as herein set forth and described.

2. A percussion or igniting strip provided 45 with a suitable flange or flanges, *d*, for securing the end of said strips between the lugs or projections on the winding-wheel of an automatic lighting device, substantially as described.

3. A percussion-strip provided with pellets of fulminating or igniting compound placed differentially throughout its length for regulating their supply to the hammer-head when operated by a winding-wheel of an automatic 55 lighting device, substantially as described.

HENRY F. MEGILL.
